UNITED STATES PATENT OFFICE.

CLARENCE E. HAWKE, OF NEWTOWN, NEW JERSEY, ASSIGNEE TO THE CARBONITE
PIPE COMPANY, OF NIAGARA FALLS, NEW YORK, A CORPORATION OF PENNSYLVANIA.

ARCH BRICK AND ARCH.

Application filed February 17, 1923. Serial No. 610,887.

To all whom it may concern:

Be it known that I, CLARENCE E. HAWKE, a citizen of the United States, residing at Newtun, county of Middlesex, and State of New Jersey, have invented a new and useful improvement in Arch Bricks and Arches, of which the following is a full, clear, and exact description.

This invention relates to arch brick, and is particularly adapted for use in the arches of muffle furnaces and the like. In such furnaces, a brick of high heat conductivity and high mechanical strength is very desirable, particularly in the furnace arch.

My invention utilizes an arch brick of silicon carbide instead of the refractories commonly used. Silicon carbide has a high mechanical strength which is not materially affected by elevated temperatures, is capable of being made into gas-tight bricks, and has a high thermal conductivity. It is, therefore, particularly adapted for use in muffle ovens.

The invention provides a brick having ribs, preferably on the under side of the arch. This results in an arch having a relatively thin body portion, thereby materially increasing the rate of heat transfer. The ribs supply the mechanical strength required to support the arch, and in addition, provide an increased radiating surface.

The bricks are preferably made with a plurality of spaced ribs, by which it is possible to half-space or otherwise bond the bricks in the arch, while the ribs register with one another to form a plurality of continuous ribs across the arch.

In the accompanying drawings, illustrating the preferred embodiment of my invention:

Figure 1 is a vertical section through a conventional muffle furnace embodying my invention.

Figure 2 is a vertical section on the line II-II of Figure 1.

Figure 3 is a top plan view of a portion of the arch, and

Figures 4, 5, 6, 7 and 8 are detail views of arch bricks made according to my invention.

In the illustrated embodiment of the invention, a muffle or working chamber 2 is provided in a furnace 3 having a combustion chamber 4. Heat from the combustion chamber 4 passes around the walls and over

the arch 5 of the working chamber 2 to the stack 6. The arch 5 is constructed of bricks, preferably of silicon carbide, having a thin body portion 7 to facilitate heat transfer to the working chamber 2.

The bricks are provided with suitable beads 8 and recesses 9 around the edges of the body portion 7. These beads and recesses serve to interlock the bricks when they are assembled as an arch, securely holding them in place and tending to make the arch gas-tight.

The bricks are further provided with ribs 10. These ribs are preferably on the under side of the bricks, since this construction leaves the arch smooth on the outside and ensures a free movement of the hot gases over the arch with a corresponding increase in the efficiency of the furnace.

The ribs 10 are equally spaced, and in addition are spaced from the ends of the bricks half the distance between ribs. As shown in Figure 3, such a construction permits a lapping or bonding of adjacent courses 11 of the bricks, and at the same time supplies continuous ribs across the arch of the furnace. The alternate courses are started with half bricks such as shown in Figure 3.

The advantages of my invention arise from the provision of a ribbed brick capable of being bonded in the arch, and at the same time forming continuous ribs across the arch. Further advantages arise from the use of silicon carbide as a material for the bricks, and these combine to form an arch of high thermal efficiency and great mechanical strength.

While I have shown one embodiment of my invention as applied to a muffle furnace, it will be understood that it is not limited thereto, but may be embodied in other constructions within the scope of the following claims.

I claim:

1. An arch brick comprising a body portion and a plurality of equally spaced ribs, the end ribs being spaced from the ends of the brick one-half the distance from rib to rib.

2. An arch brick, comprising a body portion and a plurality of equally spaced ribs adapted to lie on the under side of the arch, the end ribs being spaced from the ends of the brick one-half the distance from rib to rib.

- 2
- 3. An arch brick, comprising a body portion and two ribs, the ribs being spaced from the ends of the brick one-half the distance between ribs.
  - 4. An arch brick, comprising a body portion and two ribs adapted to lie on the under side of the arch, the ribs being spaced from the ends of the brick one-half the distance between the ribs.
  - 5. An arch comprising a plurality of bricks of substantially uniform length laid in courses parallel to the length of the arch, the bricks in each course being offset half the length of a brick with respect to the adjoining course.

ing course, and each brick having two ribs ¹⁵ perpendicular to the courses and adapted to align with the ribs of adjacent bricks to form a plurality of continuous ribs across the arch.

6. An arch brick comprising a body portion and a plurality of equally spaced ribs, the end ribs being spaced from the ends of the brick one-half the distance from rib to rib, and interlocking means around the edges of the body portion. ²⁰

In testimony whereof I have hereunto set my hand. ²⁵

CLARENCE E. HAWKE.
